UNITED STATES PATENT OFFICE

156,959

HEAT APPLICATOR OR SIMILAR ARTICLE

Emil Hofman, Newark, N. J.

Application October 1, 1947, Serial No. 141,705

Term of patent 14 years

(Cl. D83—1)

To all whom it may concern:

Be it known that I, Emil Hofman, a citizen of the United States, residing in the city of Newark, county of Essex, and State of New Jersey, have invented a new, original, and ornamental Design for a Heat Applicator or Similar Article, of which the following is a specification, reference being had to the accompanying drawing, forming a part thereof.

Figure 1 is a front elevation of a heat applicator or similar article embodying my new design,

Figure 2 is a side elevation,

Figure 3 is a top plan view,

Figure 4 is a bottom plan view thereof; and

Figure 5 is a cross section on line line 5—5 in Figure 1.

I claim:

The ornamental design for a heat applicator or similar article, as shown.

EMIL HOFMAN.
